Primary Examiner — Zenia I Bennett(74) *Attorney, Agent, or Firm* — AP Patents(57) **CLAIM**

The ornamental design for a snap button, as shown and described.

DESCRIPTION

FIG. 1 illustrates a top view of a snap button constructed in accordance with one embodiment;

FIG. 2 illustrates a bottom view of the snap button of FIG. 1;

FIG. 3 illustrates a right side elevation view of the snap button of FIG. 1; Left side, front and rear views are identical; FIG. 4 illustrates a cross-sectional view of the snap button of FIG. 1 along lines 4-4 of FIG. 3; and,

FIG. 5 illustrates a rear 3-dimensional view of the snap button of FIG. 1; The broken lines showing indicia and substrate and/or the mating portion that the button is attached to are for environmental purposes only and form no part of the claimed design.

1 Claim, 2 Drawing Sheets---
